RECORD CONTROLLED PRINTING MACHINE

Michael Maul, Berlin-Biesdorf, Germany

Application May 25, 1931, Serial No. 539,365
In Germany June 3, 1930

29 Claims. (Cl. 101—58)

The present invention relates to automatic record controlled machines and more particularly to a machine of a novel type which is under the joint control of index marks associated to records and of index marks associated to data carriers and wherein transferring means are provided for transferring the data represented on said data carriers, said data being preferably transferred upon said records themselves to which said index marks are associated.

10 The records may be provided as record cards or sheets or sections of a continuous record sheet and the index marks of said records may for instance comprise perforations arranged according to any desired system such as the single hole or hole combination system.

15 Data carriers of various forms have been used in record controlled machines and accordingly the transferring means must be adapted to said data carriers. If the data are carried on a record card and are represented by perforations on said card, the transferring mechanism must include analyzing means and printing means controlled thereby so that the data may be analyzed from 20 the perforated record card and printed. Of course, machines of the type referred to have also been suggested wherein a punching mechanism takes the place of the printing mechanism so that the data may be entered by perforations 25 upon the data receiving records. If the data carrier takes the form of an address plate a simple printing mechanism including a printing platen will serve as transferring mechanism to print the data such as the name and address embossed upon 30 said address plates.

35 While transferring of said data can be effected upon any desired record, particular advantages result from transferring of said data upon the same records which control the machine jointly with the data carriers, as will still be described.

40 The index marks may be medately or immediately associated to said data carriers and may comprise perforations arranged according to any desired system or they may comprise tabs or the like provided on the address plates.

45 One of the main objects of the present invention is now to provide a machine adapted for selective operation in any one of two different ways, in which the records are fed through the machine and the data carriers are also fed through the machine. There must be at least for each record a data carrier but the number of records may be less and usually is less than the 50 number of data carriers with identical designations, though, with the present invention a plurality of records of each designation may be present. The records and data carriers must be supplied in raising or falling sequence of their 55 designations or numbers represented by the in-

dex marks associated to the records and the data carriers.

5 Operation I.—The machine is adjusted for this manner of operation if there is only a single record for each index mark designation present so that accordingly each data carrier is used only once in each run of all data carriers through the machine.

10 Operation II.—There may be instances where a plurality of records having the same index mark 10 designations follow each other and where it is desired to transfer the data from a single data carrier upon control of the machine by each of 15 said consecutive identical records so that the same data are repeatedly entered. In this instance 15 the machine can be adjusted to "Operation II."

20 In practice it is always known if in a series of records each designation occurs only singly or several times and the machine may be adjusted accordingly either to "Operation I" or "Operation II". This possibility of adjustment is most desirable since on the one hand it permits with 25 the Operation II as compared to I a multiple data entering and on the other hand with the Operation I a higher operating speed as compared to II.

25 In the present machine the transferring of the data depends from the result of the comparison of the index marks associated to the controlling records and of the index marks associated to the 30 data carriers and the feeding means for said records and the data carriers are also under the control of said comparing means. Upon disagreement of said index marks said transferring mechanism and record feeding means remain 35 inactive and cause only actuation of the data carrier feeding means while upon agreement of 40 said index marks said comparing means cause actuation of the transferring mechanism and actuation of the record feeding means.

45 Now, according to the invention further means are provided for selectively changing the control of the comparing means upon the data carrier feeding means to render upon agreement of said index marks said data carrier feeding means 45 inactive or to cause actuation of the same and in this way selective adjustment of the machine to "Operation I" or "Operation II" is obtained.

50 A further object of the invention is to provide a machine of the type referred to wherein the data transferred by said transferring mechanism are printed upon the entry receiving records.

55 Another object is to provide a machine of the type referred to wherein the data carriers are represented by printing devices of any desired type and more particularly by address plates having the name and address embossed thereon.

60 A further object of the invention is to cause said transferring mechanism to transfer the data upon the controlling records themselves particu-

larly if the data carriers assume the form of address plates.

The advantages of the invention are particularly obvious if the same is applied to an automatic addressing machine for perforated records. However, in its broad aspects the invention is by no means limited to that application but broadly provides a selective change of the control of comparing means for index marks upon the feeding means for records of different classes.

Broadly, it may therefore be said that one of the most important objects of the invention is to provide in an automatic machine being under the joint control of index marks on records of one class and of index marks of records of another class means for comparing the index marks of a record of the one class with the index marks of a record of the other class and to control the feeding means depending upon the result of said comparison, wherein selective means are provided to obtain either "Operation I" or "Operation II". Upon disagreement of said index marks said feeding means for the records of the one class remain inactive and actuation of the feeding means for the records of the other class is caused while upon agreement of said index marks said comparing means cause actuation of the feeding means for the records of the one class. In order to obtain the selection of the manner of operation, means are provided for selectively changing the control of the comparing means upon the feeding means for the records of the other class, to render upon agreement of said index marks said feeding means for the records of the other class inactive or to cause actuation of the same to feed the subsequent record of the other class.

A further object of the invention is to provide a machine of the aforesaid type wherein the records having index marks associated thereto comprise perforated records.

A further object is to provide in a machine of the type referred to means for taking a reading from said records, said means being also under the control of said comparing means.

Still a further object is to provide in a machine of the type referred to a printing mechanism being under the control of said comparing means.

A further important object of the invention is to provide an automatic addressing machine permitting selective operation as indicated and wherein the address plates are preferably printed upon the same perforated records controlling the machine jointly with the index marks associated to said address plates.

While the provision of a machine of the character indicated above which permits selective operation in any one of two different manners, is one of the most important objects of the invention, it is also a very important object of the invention to provide an automatic addressing machine which permits, if so desired, only the "Operation II" as indicated above, whereas the "Operation I" per se forms the subject matter of my copending application Serial No. 524,896, filed March 24th, 1931, of which the present case is an improvement.

Accordingly, another object of the invention is to actuate upon agreement of said record perforations with said index marks only the record feeding means while upon disagreement the record feeding means remain inactive and the address plate feeding means are actuated.

Further objects of the invention are common to all aforesaid types of machines.

Accordingly, a further object of the invention is to provide machines of the type referred to wherein a perforated record and an address plate are simultaneously analyzed by the comparing means while both the address plate and the record are in printing position.

A further object is to provide comparing means including electrical analyzers for the perforated records and mechanical analyzers for the address plates.

A further object is to provide machines of the type referred to which respond to perforations and index marks provided according to the combinational system.

A further object is to provide machines of the type referred to adapted to operate with a continuous record sheet having designation perforations spaced apart along said sheet and still a further object is to provide analyzer means adapted to detect guide holes of said sheet, one hole being coordinated to each designation perforation and controlling the operation of the feeding means as well as the initiation of the comparing operation.

A further object is to provide the designation perforation analyzer means of the comprising mechanism and the guide hole analyzer adjustable relatively to printing position so that the address may be printed within a predetermined range at any desired distance from the designation perforation.

The invention may be advantageously used in work of various sort and for this reason only an illustrative example will now be given and will be explained more in detail in the specification.

If, for instance, statements of accounts, gas or electricity bills or the like are prepared the same may be addressed with the machine according to the present invention even if there are a plurality of statements present having the same designation. The statements are provided with designation perforations and are fed through the machine one by one in raising or falling order; for each designation must be an address plate present, but it is not necessary that for each address plate there must be a statement with the corresponding designation perforation. If the address plates are fed through the machine in the same order as the statements, the latter will be properly and automatically addressed by the machine as will still be described herein more in detail.

The application of the addressing system in connection with the perforated record system affords many and considerable advantages over the prior art and one instance is more fully set forth in my co-pending application Serial No. 550,939 filed July 15th, 1931 relating to a novel method of preparing statements and the like. The machine according to the present invention is particularly adapted to the requirements of said novel method but it will be clearly understood that a machine as described and claimed herein is by no means restricted to the application in said novel method but may just as well be applied in various other ways; of course, said novel method may also be carried out with various other means or machines notwithstanding the fact that the present printing machine is highly preferable for said purpose.

Further objects and advantages of the invention will be seen from the following specification and claims.

As far as in the specification and claims refer-

ence is made to "address plates" it will be understood that this term shall include any type of equivalent printing instruments serving the same purpose such as stencil cards or the like bearing 5 a name or the name and the address, or other identifying matter.

The annexed drawings represent a preferred embodiment of the invention which will now be described.

10 In the drawings:

Figs. 1a and 1b represent a top view of the addressing machine according to the invention.

Figs. 2a and 2b represent a section through the machine shown in Figs. 1a and 1b. Figs. 1a, 1b 15 and Figs. 2a, 2b respectively belong together.

Fig. 3 is a section on line 3—3 of Fig. 1b and shows the drive mechanism of the machine.

Fig. 4 shows in an enlarged scale the analyzing device for the index marks of the address plates, 20 said marks being provided in the form of hole combinations.

Fig. 5 represents the scheme according to which the numerals in the sheets to be addressed and in the address plates are represented by 25 different hole combinations.

Fig. 6 shows the circuit diagram of the machine.

Address plates and record sheets to be addressed

30 The address plates (Figs. 1a, 1b, 2a, 2b) are fed from the magazine 10 through the machine to the receptacle 12. Each plate is provided with a perforation representing the plate number and being arranged in accordance with 35 the key shown in Fig. 5. This perforation may of course be replaced by tabs or may be provided upon a card inserted in a frame carrying the address plate. The record sheets to be addressed may be in the form of cards, lists and 40 so on and are perforated in accordance with the same key as the sheets; each record column comprises four hole positions within which a numeral may be represented by a single or combinational holes. The lists are also provided with a standard point hole being provided at the level of the 45 lowermost hole position of a hole combination and serving as standard point with relation to the hole combination.

50 *Driving mechanisms of the addressing machine*

The machine is driven by the motor 15 (Fig. 3) through the worm 16. The plates 11 are fed by a slide 18 (Figs. 2b, 3) from the right to the left through the machine. The slide 18 is actuated by means of parts 59, 62, 61 by a lever 57 being under the influence of a spring 58; said lever is pivotally mounted at 56 and is rocked about its pivot under the control of a cam disk 54 upon which the roller 55 rides. The cam disk 54 is driven by means of gears 52, 53 and the one-revolution clutch 49, 50 provided upon the shafts 48, 60, said one-revolution clutch being controllable by magnet 63 by means of a pin 51 and lever 64 coacting with a spring 65. The 60 shaft of the disk 54 carries a cam 134' closing in the home position of said disk a contact 134. The shaft 48 is driven by worm 16 through worm-gear 41. The one-revolution clutch 37, 38 (Fig. 2b) for the printing mechanism is controlled by 65 means of parts 45, 39, 40 by the magnet 41. The shaft 36 of the clutch member 37 is driven by worm 16 through the wormgear 35. The lever 40 has a downwardly extending member 65 which, as will still be described, is adapted to control the clutch member 64 of the one-revolution clutch 49, 70

50 for the plate feeding mechanism. In the front and rear wall of the casing is a shaft 196 mounted adapted to be adjusted into any one of two shift positions; the shaft is provided with a spring actuated pin 195, engaging in the one shift position of the shaft between the arms 65 and 64. Upon the shaft 196 is fastened on the outside of the machine (Fig. 1b) a handle 192. If the parts are in the position shown in Figs. 1b and 2b the arm 65 will freely move upon energization of the magnet 41 and no influence upon the arm 64 will be effected. The handle 192 must be adjusted in this position if the mechanism shall be adapted to print the same address upon a number of subsequent lists having identical perforations. However, if the machine shall be shifted to the other manner of operation (if each identification perforation occurs only once in the series of record sheets) the lever 192 must be turned for one fourth revolution in 20 clockwise direction so that the pin 195 will move between the arms 64 and 65. Accordingly, upon each energization of magnet 41, also the one-revolution clutch 49, 59 for the plate feeding mechanism will be released by means of pin 195 25 so which will be moved to the right by arm 65 so that simultaneously with or after each printing operation respectively also the next record sheet will be immediately advanced.

The printing cushion 18' is fast on the plate 30 19 (Figs. 1a, 2a) which is connected by means of parts 20, 21, 22 to the arm 23 which is integral with sleeve 25 and arm 26, the roller 27 of which is riding under the influence of spring 28 upon the cam disk 29; the cam disk can be driven 35 over shaft 30 and bevel gears 31, 32 and shaft 33 by means of the one-revolution clutch 37, 38 to perform one printing cycle. Upon the shaft 33 are fast two cams 131' and 132'; after completion of the printing operation the first cam closes 40 temporarily the contact 131 and the last mentioned cam keeps the contact 132 closed if the machine is in home position. The sleeve 25 is pivotally mounted upon the shaft 24 which is fastened to the bracket 25'. The address plates 45 are advanced in the channel 17 (see Fig. 2b) and by means of a ribbon 19 (Fig. 2a) they are printed upon the lower side of the record sheet which is fed between the printing cushion 18' and the ribbon 19'. 50

The record sheets are inserted by means of hand wheels 72 and 73' and are fed by rollers 70 and 71 (the first ones operating as drive rollers) over the table 190 of the addressing machine thereby closing the contact 137 (Fig. 6) which is under the control of a lever 136. The feed of the sheet is effected by means of a clutch 74, 75 (Figs. 1b, 3); said clutch is driven by a wheel 73 through worm 16 and is operatively connected through gears 76 and 77 with the feed rollers 70. 60 The clutch is under the control of the magnet 78 controlling the clutch mechanism 79—83 which on its part closes upon energization of magnet 78a contact 84. Upon energization of magnet 130 a frame 128, pivotally mounted at 129, will be 65 rocked; the fingers 126', 127' of said frame are adapted to close the contacts 126 and 127 under the control of the spindle 16.

Comparing mechanism for record sheet perforations and address plate perforations 70

All hole positions of a record list and of an address plate are simultaneously electrically analyzed and the two current circuits coordinated to each hole position control two oppositely act- 75

ing windings of an electromagnet so that upon agreement said windings will be compensated and no controlling effect will be caused thereby while in the other instance a controlling operation will be effected. The respective magnets which are indicated in Fig. 3 at 120, control the plate 132 which is pivotally mounted at 121 and which normally keeps the contact 124 closed under the influence of a spring 123; upon energization of one or a plurality of the magnets 120, however, the contact 125 will be closed.

The analysis of the record sheet perforations, is effected by means of the analyzing brushes 90 (Figs. 1a and 1b); for each record column there are four brushes provided in a vertical row. The standard point hole of each list is analyzed by the brush 95. The brushes 90, 95 cooperate with a contact plate 94 and are fastened on an insulating block 91 being adjustable along the adjusting bar 93 by means of the set screw 92.

The analyzing mechanism for the address plate perforations is shown more in detail in Fig. 4, illustrating the arrangement for one record column. The pins 101 for the analysis of the address plate perforations are slideable in a plate 100 and are guided by the inner ends of levers 102 which are pivotally mounted at 103 and which are under the influence of springs 112. The levers 102 are held by means of springs 106 and a frame 104 in their lower position through a cross bar 105 and are only released for analysis if due to the energization of magnet 109 the core and accordingly also the pin 11 and the frame 104 are raised, and at the end of said movement the contact 135 will be closed. On each position on which there is a perforation in the address plate the contact 107 coordinated to the respective hole position will be closed.

Circuit diagram

The current source 138 may be connected by the main switch to the main lines 139 and 140 to which the motor 15 is directly connected. From the contact 137 leads over stop contact 141 a line 142 terminating in contact 127 which again is connected by line 143 to the middle plate spring of the shiftable contact 124, 125. From the right side of the contact 124 a line 144 leads to the clutch magnet 50 (for the printing mechanism) which is connected to the main line 140. The left side of the normally open contact 125 is connected by a line 145 with the clutch magnet 63 (for plate feeding) which in turn is also connected to the line 140.

The analyzing and comparing mechanism is inserted into the current circuit as will now be described: As will be seen from the circuit diagram, each magnet 120 comprises two windings. In the circuit of the one winding of each magnet lies the contact of the coordinated brush 90 with the contact plate 94 while the circuit of the other winding is controlled by the contact 107 (see also Fig. 4). The plate 94 is connected by a line 148 with line 142 and the brushes 90 are connected by lines 149 with the one ends of their coordinated windings. The terminals of said windings are connected by common lines 150, both upper lines 150 leading to a common line 151 and both lower lines 150 leading to a common line 152. The lines 151 and 152 are connected to a common line 153 leading to the contact 126 which in turn is connected over line 154 with the lower main line 140. The address plate controlled magnet windings of both upper sets

of magnets are connected by lines 156 and 157 directly to the upper line 142 while the corresponding entries of both lower sets are over line 158 in connection with line 142. The terminals of said windings in which the contacts 107 are arranged are connected as shown in Fig. 6 by common lines to the lines 151 and 152 which are connected to the line 153. It will be seen that from the positive pole (line 142), over line 148, contact plate 94 and brushes 90 the list perforation controlled magnet windings are connected over line 153, contact 126 and line 154 with the negative pole (line 140) of the current source; on the other hand, the address plate perforation controlled windings of the magnets 120 are connected with their entries by lines 156, 157 and 158 to the positive pole (142) while their terminal lines in which the contacts 107 are arranged are connected with line 153 leading in the above described way to the negative side (140) of the current source. Accordingly, the comparing magnets 120 are controlled by the sheet perforations as well as by the perforations of the address plate in such a way that these perforations control closure of the contacts 90, 94 and 107 respectively; if these contacts are closed, no current circuit is yet established since the completion of the current circuit is controlled by contact 126 arranged in the common back line of all magnets; it is only if the circuits of the magnets have been prepared by the perforations of the list as well as by the perforations of the address plate that by closure of contact 126 the comparing circuit may be finally completed so that the windings of the magnets 120 may be energized.

To the line 142 is the magnet 130 connected which in turn is connected by a line 162 over contact 135 with the line 140 so that the magnet 130 will be energized if due to the energization of the solenoid 109 the contact 135 is closed.

For the control of the paper feed, the brush 95 cooperating with the contact plate 94, is connected by line 163 with the relay 164 which in turn is connected over line 165 to line 140.

The armature 166 of relay 164 establishes in the deenergized state of the relay a connection between the line 165 and the line 167 leading to the contact 84; however, if the relay 164 is energized its armature closes the contact 168 thereby connecting the line 169 with the line 170 leading to the contact 134. From the contact 134 leads a line 171 to the contact 132 and from said contact leads a line 172 to the solenoid 109 which is connected to the negative side 140 of the current source. From the line 169 branches a line 173 to the clutch magnet 78 for the record sheet feed, said magnet being connected to a line 174 leading over the start key controlled contact 175 to the negative line 140. To the line 174 is connected on the one hand the contact 84 and on the other hand over a line 176 the contact 131, the other side of said contact being over a line 177 in connection with line 140.

Operation of the machine

Now at first the case shall be described if the machine is shifted to the manner of operation where each identification perforation of the record sheets occurs only once; for this manner of operation, the lever shown in Fig. 1b is turned to the right for one fourth revolution so that the pin 195 (Fig. 2b) establishes an operative connection between the links 65 and 64.

If the machine is in rest position all parts are in

the position shown in the drawings and the electrical connections as shown in the circuit diagram are established. The address plates are inserted in the magazine 10 (Fig. 1b) with their 5 relief side upwardly directed, the plate with the lowest account number lying lowermost while the plates with numbers increasing in current numerical order are following. The operator feeds the unprinted leading end of the continuous 10 record sheet between the rollers 10 and 11 by means of the previously described handwheels in such a way that the sheet lies with its printed side upon the table of the machine. The record sheet is inserted with the end having the lowest 15 account number so that the lists with raising account numbers will follow. If addressing is to be effected in the reverse order, of course, also all address plates must be inserted in the machine in reverse order. If the record sheet is tightly 20 tensioned upon the table 190 of the addressing machine, the contact 137 is closed by contact lever 136 (see Fig. 6) thereby connecting the electrical mechanisms of the machine with the current source. It must still be mentioned that 25 in this initial position of the record sheet all brushes 90 and also the brush 95 are insulated from the contact plate 94 since the leading end of the record sheet shall not be punched so that in the start position of the sheet there are no 30 holes under the brushes.

In order to start the machine for operation, the operator depresses the start key 175' (Fig. 6) thereby closing the contact 175. Consequently, the clutch magnet 18 for the sheet feed receives 35 current from the lines 169, 173, flowing then over line 174 and contact 175 to the negative line 140. The magnet 178 will therefore be energized and will engage in the previously described manner the clutches 74, 75, thereby operating the feed 40 rollers 10 to feed the record sheet upwardly (Figs. 1a, 1b). Due to the energization of magnet 18 the contact 84 will be closed, said magnet establishing thereby its own stick circuit over the contact 84, line 167, armature 166 of relay 164 and line 165 so that after instantaneous actuation the 45 start key 175' may again be released and the contact 175 may open again. The record sheet feed will now be maintained in operation and the sheet will be advanced by the feed rollers 10 until a standard point hole comes under the 50 brush 95 (Figs. 1a, 2a). In this moment a current impulse will be released from line 142 (Fig. 6) over line 148, contact plate 94, brush 95, line 163, relay 164 and line 165 to the negative line 55 140, and said impulse will energize relay 164. Consequently the armature 166 will be drawn to the left so that the stick circuit of clutch magnet 18 leading over line 167 and armature 166 will be immediately interrupted, thereby disengaging 60 the clutches 74 and 75, and interrupting the record sheet feed operation. The continuous record sheet will therefore be stopped so that the standard point hole will be arrested under the brush 95 and all predetermined hole positions of the list now being in printing position 65 will be under the analyzing brushes 90 for the list perforations. Due to the energization of relay 164 the contact 168 has been closed and since also the contacts 134 and 132 of the coordinated 70 mechanism (now being in home position) are closed, a current will flow over line 169, contact 168, line 170, contact 134, line 111, contact 132, line 172 through the solenoid 109 to the line 146. The solenoid 109 will be energized and will lift its 75 armature so that in the previously described

manner analysis of the address plate feeding channel will be effected by means of pins 101 (Figs. 2a and 4). Due to the energization of the solenoid 109 the contact 135 will be closed after the address plate feeding channel has already 5 been analyzed so that the magnet 180 will be energized over line 162. Consequently the frame 128 will be drawn upwardly and the previously described fingers will engage the worm 16 and will be moved to the right. Soon afterwards the 10 contact 126 will be closed and a little later also contact 121. As has been mentioned above, the 15 current circuit of the comparing magnets will be completed through contact 126. Since now, at the beginning of the addressing work, no address plate is in printing position, there will be no 20 agreement with the perforations of the list being in printing position, and consequently thereof one or a plurality of the magnets 120 will become effective in the moment in which the contact 25 126 closes. The armature plate 122 will be rocked by said magnets 120 in counterclockwise direction so that the contact 124 opens and the contact 125 will be closed. Timing is provided 30 in such a way that shifting of the contacts 124 and 125 is already completed if the contact 127 is closed by its coordinated slide. In the above 35 assumed case, i. e. if no address plate is yet in printing position, upon closure of contact 127, a current will be sent over line 142, contact 127, line 143, contact 125, line 148 and clutch magnet 63 to the negative line 140 so that by the energization of clutch magnet 63 the one-revolution clutch 49, 50 will be engaged and a plate feeding 40 cycle will be initiated. In the moment in which the one-revolution clutch 49, 50 is engaged, the contact 134 will open due to the cam 134' now moving from its home position so that the current circuit of the analyzing magnet 109 will open which in turn causes opening of contact 135. 45 Consequently thereof, also magnet 180 will become deenergized and the frame 128 will return to its home position thereby also opening immediately the contacts 126 and 127. The magnets 120 will become deenergized and instead of 50 contact 125 the contact 124 will again be closed. It will, however, be noticed that in the current source of the solenoid 109 no contact is open besides the contact 134. The contact 168 is still held closed by the relay 164 since the standard 55 point hole is still under the brush 95. On the other hand, also the contact 132 is still closed since the one-revolution clutch 37, 38 for the printing mechanism is not yet engaged. If now a plate has been advanced after one revolution 60 of the cam disk 54, the contact 134 will again be closed by the cam 134' and thereupon the solenoid 109 will again be energized. This causes in the above described way closure of the current circuit of magnet 180 and consequently 65 thereof closure of the contact 126 for actuation of the electric comparing mechanism. If then there is still no printing plate in printing position, magnet 63 will again be energized, a new plate feeding cycle will be initiated and the solenoid 70 109 will be deenergized by closure of contact 134. These operations will continue until the first printing plate reaches the printing position; it will be clearly seen that even if said printing plate is not provided with perforations corresponding to those of the list still being in printing position, the next plate will be advanced. If it is now assumed that for instance after a number of plate feeding cycles a plate comes into 75 printing position the identification perforation of

which agrees with the identification perforation of the list still being in printing position, the following operations will take place:

At the end of the preceding plate feeding cycle 5 the contact 134 has been closed thereby deenergizing the solenoid 109. Consequently thereof, the contact 135 will have been closed and the magnet 130 will have been energized which in turn causes closure of contacts 126 and 127 in time sequence. If now the perforations of the list and of the address plate being in printing position are in agreement, both windings of the magnets coordinated to the perforated positions will be compensated while on all imperforate positions no energization of magnets will be effected at all; accordingly the armature plate 122 will remain in the position shown in Figs. 3 and 6 and the contact 134 will also remain closed. If then contact 127 is closed a current will flow from line 142 over contact 127, contact 124, line 144 and clutch magnet 41 to the negative line 140; due to the energization of magnet 41 the one-revolution clutch 37, 38 of the printing mechanism will be engaged. In the previously described mechanical way, however, simultaneously therewith also the one-revolution clutch 49, 50 for the plate feed mechanism will be engaged. During the first quarter of the operating cycle printing of the address plate being in printing position will be effected upon the list being in printing position, and during the second and third quarter of the operating cycle the next plate will be advanced into printing position. Since upon release of both one-revolution clutches the contacts 134 and 132 will open, of course, also the magnets 109 and 130 will immediately be deenergized. After printing has been effected by the printing cam 29, the cam 131' will encounter the contact 131 thereby establishing a shunt circuit to the start contact 175 and deenergizing immediately (still during the same operating cycle) the clutch magnet 78 for the sheet feeding mechanism. This magnet establishes then (if contact 131 opens again after having been left by the cam 131') over contact 84, line 167, relay armature 166 and line 165 its own stick circuit; it must be mentioned in this connection that the contact 131 remains closed until the record sheet feeding mechanism having been engaged in the meantime has already moved the standard point hole away from the brush 95 and that due to relay 164 which has been deenergized thereby, a connection will again be established by armature 166 between line 167 and line 165 before contact 131 opens. It will be clearly seen that immediately after the first quarter of the machine cycle after printing has been effected the sheet feeding operation is initiated while the plate feeding mechanism is still in rest position. By the feeding mechanism the next list will now be advanced and as soon as the standard point hole 14 of the next list comes under the brush 95, the relay 164 will again be energized so that the stick circuit of the clutch magnet 78 for the record sheet feed is interrupted and the list will again be stopped in printing position. However, simultaneously therewith also the contact 168 will be closed; independently thereof whether the operating cycle of the printing and plate feeding mechanism or the operation of the paper feed mechanism is completed first, it is only if both operations are actually completed and if all parts are again in home and rest position that the solenoid 109 will again be energized since its circuit includes as well the contact 168 as the contacts 134 and 132. Due to the energization of the solenoid 109 another comparing cycle will be initiated and depending upon the result of said comparison either the contact 124 remains closed or the contact 125 will be closed. If the contact 125 is closed, upon closure of contact 127 only the plate feeding mechanism will be released electromagnetically and the next address plate will be advanced into printing position while the list will stay in its position 10 since the shaft 33 of the printing mechanism is not rotating and consequently thereof also contact 131 will not be closed. However, if the identification perforations are in agreement, the line 143 remains connected with the contact 124 and 15 clutch magnet 41 will be energized which releases the plate feeding mechanism as well as the printing mechanism; depending upon the latter the paper feed mechanism will then again be automatically engaged after completion of the 20 printing operation, and a new list will be fed into printing position. It will be clearly seen that all these operations will be repeated in automatic and uninterrupted sequence so that the proper addresses will be printed upon the lists 25 which are fed through the machine one by one.

If the machine shall be adjusted to the manner of operation where a plurality of lists having identical identification perforations may occur, the lever 192 and pin 195 must be adjusted to the 30 position shown in Fig. 2b so that the pin 195 is in vertical position and the one-revolution clutch 49, 50 is mechanically independent from the one-revolution clutch 37, 38, each clutch being then only releasable by its coordinated magnet 41 or 63 respectively. Starting of the operation is then effected in the same way as has been described in connection with the other manner of operation and finally the regular addressing operations will take place. Upon agreement of the 40 perforations the one-revolution clutch 37, 38 will be released, due to the energization of magnet 41 and due to said release a printing cycle will be initiated; in the course of said cycle the contact 131 (Fig. 6) will be closed by a rotating cam 131' 45 thereby initiating the record sheet feeding operation. It will, however, be seen that in the present instance (contrary to the other manner of operation) the clutch 49, 50 for the plate feeding mechanism will not be released. Accordingly, 50 a new list will be advanced, and the interruption of the feeding operation will be effected under the control of the standard point hole of the next list, said hole being analyzed by the brush 95. If now the next list bears the same identification perforation as the preceding list, i. e. if its perforation agrees with the perforation of the address plate still being in printing position, the contact 124 will remain closed and only magnet 41 will again be energized thereby initiating another printing 60 cycle in the course of which the contact 131 will again be closed to initiate another record sheet feeding operation. The address plate will then still remain in printing position since the clutch for the plate feeding mechanism has not 65 been released. These operations will continue as long as the subsequently advanced lists agree with the address plate still remaining in printing position, and accordingly the same plate will be printed upon a number of consecutive lists. If 70 now finally a list with a higher identification number has been advanced, its identification perforation will not agree with the poreformation of the address plate being in printing position. Accordingly, as a result of the comparing oper- 75

ation, the contact 125 will be closed and due to the energization of magnet 63 only the clutch 49, 50 will be released thereby initiating a plate feeding cycle. The next plate will now be advanced

5 and the same will be compared with the list being
in printing position. If there is no agreement of
the respective perforations which is the case if
from the preceding list to the list just being in
printing position there was a gap in the running
10 identification numbers, the magnet 63 will be en-
ergized and the next plates will be advanced one
by one; these operations will continue until the
list is the same number as the list in print-

plate having the same number as the last printing position has arrived at the analyzing station. 15 Then there is again agreement and printing will be effected. Subsequently to this printing operation, however, the address plate will remain in printing position and as has been described, the

20 next list will be advanced. If now there is no agreement of the perforations, the next address plate will be advanced while upon agreement printing will be effected and the next record sheet will only be advanced, and in this manner the operating cycles will automatically continue.

25 The invention is, of course, by no means limited to address plates having the index marks immediately provided thereon but it may be executed as well by means of an accounting mechanism physically indicating the identification numbers of the address plates being in printing position, said accounting mechanism being shifted step by step in accordance with the feeding operations of the address plates.

30

address plates. While there have been shown and described and pointed out the fundamental novel features of the invention it will be understood that many changes and alterations and substitutions in the machine and in its operation may be made without departing from the spirit of the invention.

40 What I claim is:

1. In an automatic machine being under the joint control of index marks on records of one class and of index marks of records of another class, means for comparing the index marks of a record of the one class with the index marks of a record of the other class, means for feeding the records of the one class one by one to comparing position past said comparing means and means for feeding the records of the other class one by one to comparing position past said comparing means, means under the control of said comparing means for causing upon disagreement of said index marks said feeding means for the records of the one class to remain inactive and to cause actuation of the feeding means for the records of the other class to feed the subsequent record of said other class to comparing position while upon agreement of said index marks said comparing means cause actuation of the feeding means for the records of the one class to feed the subsequent record of said class to comparing position, and means for selectively changing the control of said comparing means upon the feeding means for the records of the other class to render upon agreement of said index marks said feeding means for the records of the other class inactive or to cause actuation of the same to feed the subsequent record of the other class to comparing position.

70 2. In a machine as specified in claim 1, driving means between the driving and feeding means for the record of the one class and a clutch between the driving means and the feeding means for the records of the other class, each clutch being controlled by said comparing means and means for

establishing control of the clutch for the records of the one class upon the clutch for the records of the other class, said latter means constituting the selective changing means.

3. In an automatic machine being under the joint control of perforated records of one class and of perforated records of another class, means for comparing the perforations of the records of the one class with the perforations of the records of the other class, means for feeding the records of the one class one by one to comparing position past said comparing means and means for feeding the records of the other class one by one to comparing position past said comparing means, and means under the control of said comparing means for causing upon disagreement of said perforations said feeding means for the perforated records of the one class to remain inactive and to cause actuation of the feeding means for the perforated records of the other class to feed the subsequent record of said class to comparing position while upon agreement of said perforations said comparing means cause actuation of the feeding means for the perforated records of the one class to feed the subsequent record of said class to comparing position, and means for selectively changing the control of said comparing means upon the feeding means for the perforated records of the other class to render upon agreement of said perforations the feeding means for the records of the other class inactive or to cause actuation of the same to feed the subsequent perforated record of the other class to comparing position.

4. In an automatic machine being under the 35
joint control of index marks on records of one
class and of index marks of records of another
class, means for comparing the index marks of
a record of the one class with the index marks
of a record of the other class, means for feeding 40
the records of the one class one by one to com-
paring position past said comparing means and
means for feeding the records of the other class
one by one to comparing position past said com-
paring means, means under the control of said 45
comparing means for causing upon disagreement
of said index marks said feeding means for the
records of the one class to remain inactive and to
cause actuation of the feeding means for the 50
records of the other class to feed the subsequent
record of said other class to comparing position
while upon agreement of said index marks said
comparing means cause actuation of the feeding
means for the records of the one class to feed 55
the subsequent record of said class to comparing
position, and means for selectively changing the
control of said comparing means upon the feed-
ing means for the records of the other class to
render upon agreement of said index marks said 60
feeding means for the records of the other class
inactive or to cause actuation of the same to feed
the subsequent record of the other class to com-
paring position, means also under the control of
said comparing means for taking a reading from 65
said records, and means for actuating said means
for taking a reading if said index marks are in
agreement and for rendering said means for tak-
ing a reading inactive if said index marks dis-
agree.

5. In an automatic machine being under the joint control of index marks on records of one class and of index marks of records of another class, means for comparing the index marks of a record of the one class with the index marks of a record of the other class, means for feed- 75

- ing the records of the one class one by one to comparing position past said comparing means and means for feeding the records of the other class one by one to comparing position past said comparing means, means under the control of said comparing means for causing upon disagreement of said index marks said feeding means for the records of the one class to remain inactive and to cause actuation of the feeding means for the records of the other class to feed the subsequent record of said other class to comparing position while upon agreement of said index marks said comparing means cause actuation of the feeding means for the records of the one class to feed the subsequent record of said class to comparing position, and means for selectively changing the control of said comparing means upon the feeding means for the records of the other class to render upon agreement of said index marks said feeding means for the records of the other class inactive or to cause actuation of the same to feed the subsequent record of the other class to comparing position, a printing mechanism also under the control of said comparing means, and means for actuating said printing mechanism if said index marks are in agreement and for rendering said printing mechanism inactive if said index marks disagree.
6. In an automatic machine being under the joint control of records having index marks and of data carriers having also index marks, a transferring mechanism for transferring the data represented on said data carriers, means for comparing the index marks on said records with the index marks of said data carriers, means for feeding said records one by one past said comparing means and means for feeding said data carriers one by one past said comparing means, means under the control of said comparing means for causing upon disagreement of said index marks said transferring mechanism and record feeding means to remain inactive and to cause only actuation of the data carrier feeding means to feed the subsequent data carrier to comparing position while upon agreement of said index marks said comparing means cause actuation of the transferring mechanism and actuation of the record feeding means to feed the subsequent record to comparing position, and means for selectively changing the control of said comparing means upon the data carrier feeding means to render upon agreement of said index marks said data carrier feeding means inactive or to cause actuation of the same to feed the subsequent data carrier to comparing position.
7. In an automatic machine being under the joint control of records having index marks and of data carriers having also index marks, a transferring printing mechanism for transferring the data represented on said data carriers by printing, means for comparing the index marks on said records with the index marks on said data carriers, means for feeding said records having index marks one by one to comparing position past said comparing means and means for feeding said data carriers one by one to comparing position, means under the control of said comparing means for causing upon disagreement of said index marks said transferring printing mechanism and feeding means for the records to remain inactive and to cause actuation of the data carrier feeding means to feed the subsequent data carrier to comparing position while upon agreement of said index marks said comparing means cause actuation of the transferring printing mechanism and record feeding means to remain inactive and to cause only actuation of the data carrier feeding means to feed the subsequent data carrier to comparing position and means for selectively changing the control of said comparing means upon the data carrier feeding means to render upon agreement of said index marks said data carrier feeding means inactive or to cause actuation of the same to feed the subsequent data carrier to comparing position.
8. In an automatic machine being under the joint control of index marks associated to data receiving records and of index marks associated to data carriers, a transferring mechanism for entering the data represented on said data carriers upon said records, means for feeding said records one by one to transferring position past said transferring mechanism, and means for feeding said data carriers one by one to transferring position past said transferring mechanism, means for comparing the index marks associated to the data carrier being in transferring position with the index marks associated to the record being in transferring position, means under the control of said comparing means for causing upon disagreement of said index marks said transferring mechanism and record feeding means to remain inactive and to cause only actuation of the data carrier feeding means to feed the subsequent data carrier to transferring position while upon agreement of said index marks said comparing means cause actuation of the transferring mechanism and actuation of the record feeding means to feed the subsequent record to transferring position, and means for selectively changing the control of said comparing means upon the data carrier feeding means to render upon agreement of said index marks said data carrier feeding means inactive or to cause actuation of the same to feed the subsequent data carrier to transferring position.
9. In an automatic machine being under the joint control of index marks associated to data receiving records and of index marks associated to data carriers, a transferring printing mechanism for entering the data represented on said data carriers upon said records by printing, means for feeding said records one by one to transferring position past said transferring printing mechanism and means for feeding said data carriers one by one to transferring position, means for comparing the index marks associated to the data carrier being in transferring position with the index marks associated to the record being in transferring position, means under the control of said comparing means for causing upon disagreement of said index marks said transferring mechanism and record feeding means to remain inactive and to cause only actuation of the data carrier feeding means to feed the subsequent data carrier to transferring position while upon agreement of said index marks said comparing means cause actuation of the transferring mechanism and actuation of the record feeding means to feed the subsequent record to transferring position, and means for selectively changing the control of said comparing means upon the data carrier feeding means to render upon agreement of said index marks said data carrier feeding means inactive or to cause actuation of the same to feed the subsequent data carrier to transferring position.
10. In an automatic machine being under the joint control of index marks associated to data receiving records and of index marks associated to data carrying printing devices, a printing

- mechanism for printing said data from said printing devices upon said records, means for feeding said records one by one to printing position past said printing mechanism and means for feeding said printing devices one by one to printing position past said printing mechanism, means for comparing the index marks associated to the printing device being in printing position with the index marks associated to the record being 5
- 10 in printing position, means under the control of said comparing means for causing upon disagreement of said index marks said printing mechanism and record feeding means to remain inactive and to cause actuation of the printing device feeding means to feed the subsequent printing device to printing position while upon agreement of said index marks said comparing means to cause actuation of the printing mechanism to print the printing device upon the corresponding 15 record and actuation of the record feeding means to feed the subsequent record to printing position, and means for selectively changing the control of said comparing means upon the printing device feeding means to render upon agreement 20 of said index marks the printing device feeding means inactive or to cause actuation of the same to feed the subsequent printing device to printing position.
11. In a perforated record controlled machine, 30 a printing mechanism for address plates having indexes, means for comparing said perforated records with said address plate indexes and means under the control of said comparing means for governing said printing mechanism and the feeding means for said records and said address plates, means being provided under the control of said comparing means for causing a repeated printing of the same address plate upon the comparison of subsequent records having the same 35 perforations.
12. In an automatic printing machine being under the joint control of perforated records and of index marks associated to address plates, a printing mechanism for taking an impression 40 from said address plates, means for feeding the perforated records through the machine and means for feeding said address plates through the machine, means for comparing the index marks associated to the address plates with the 45 perforations on said records, means under the control of said comparing means for causing upon disagreement of said index marks with said perforations said printing mechanism and record feeding means to remain inactive and to cause 50 actuation of the address plate feeding means while upon agreement of said index marks with said perforations said comparing means cause actuation of the printing mechanism to take an impression from the corresponding address plate 55 and actuation of the record feeding means, and means for selectively changing the control of said comparing means upon the plate feeding means to render upon agreement of said index marks with said perforations the plate feeding 60 means inactive or to cause actuation of the same.
13. In an automatic machine being under the joint control of records having index marks and of address plates having also index marks, a printing mechanism for taking a print from said address plates, means for comparing the index marks on said records with the index marks on 65 said address plates, means for feeding said records one by one to comparing position past said comparing means and means for feeding said address plates one by one to comparing position, means under the control of said comparing means for causing upon disagreement of said index marks with said perforations said printing mechanism and record feeding means to remain inactive and to cause actuation of the address plate feeding means while upon agreement of said index marks with said perforations said comparing means cause actuation of the printing mechanism to take a print from the corresponding address plate and causing thereafter actuation of the feeding means for the records having index marks to feed the subsequent record to comparing position, and means for selectively changing the control of said comparing means upon the address plate feeding means to render upon agreement of said index marks the address plate feeding means inactive or to cause actuation of the same to feed the subsequent address plate to comparing position.
14. In an automatic printing machine being under the joint control of perforated records and of index marks associated to address plates, means for feeding said perforated records and means for feeding said address plates through the machine, means for comparing the index marks associated to the address plates with the perforations on said records, printing means under the control of said comparing means for taking an impression from said address plates upon agreement of said index marks with said perforations and for actuating the record feeding means and causing the address plate feeding means to remain inactive while upon disagreement the printing mechanism and record feeding means remain inactive whereas the address plate feeding means are actuated.
15. In an automatic printing machine being under the joint control of perforated records and of index marks associated to address plates, a printing mechanism for taking an impression from said address plates, means for comparing said perforated records with the index marks associated to the address plates, means for feeding said perforated records past said comparing means and means for feeding said address plates past said comparing means and means under the control of said comparing means for causing said printing means to take an impression from said address plates upon agreement of said index marks with said perforations and for actuating the record feeding means and causing the address plate feeding means to remain inactive while upon disagreement the printing mechanism and record feeding means remain inactive whereas the address plate feeding means are actuated.
16. In an automatic printing machine being under the joint control of perforated records and of index marks associated to address plates, a printing mechanism for printing the address plates upon the records themselves bearing the perforations, means for feeding the perforated records through the machine and means for feeding said address plates through the machine, means for comparing the index marks associated to the address plates with the perforations on said records, means under the control of said comparing means for causing upon disagreement of said index marks with said perforations said printing mechanism and record feeding means to remain inactive and to cause actuation of the address plate feeding means while upon agreement of said index marks with said perforations said comparing means cause actuation of the printing mechanism to print the address plate upon

- the corresponding perforated record and actuation of the record feeding means, and means for selectively changing the control of said comparing means upon the plate feeding means to render upon agreement of said index marks with said perforations the plate feeding means inactive or to cause actuation of the same.
17. In an automatic addressing machine being under the joint control of perforated records and of index marks associated to address plates, a printing mechanism for printing the address plates upon the records themselves bearing the perforations, means for feeding said perforated records one by one past said printing mechanism and means for feeding said address plates one by one past said printing mechanism, means for comparing the index marks associated to the address plate being in printing position with the designation perforations of the record sheet section being in printing position, and means under the control of said comparing means for causing upon disagreement of said index marks with said perforations said printing mechanism and record feeding means to remain inactive and to cause actuation of the address plate feeding means to feed the subsequent address plate to printing position while upon agreement of said index marks with said designation perforations said comparing means cause actuation of the printing mechanism to print the address plate upon the corresponding perforated record sheet section and actuation of the record sheet feeding means to feed the subsequent record sheet section to printing position, and means for selectively changing the control of said comparing means upon the address plate feeding means to render upon agreement of said index marks with said designation perforation the address plate feeding means inactive or to cause actuation of the same to feed the subsequent address plate to printing position.
18. In an automatic addressing machine being under the joint control of perforated records and of index marks associated to address plates, a printing mechanism for printing the address plates upon the records themselves bearing the perforations, means for comparing said perforated records with the index marks associated to the address plates, means for feeding said records one by one past said comparing means and means for feeding said address plates one by one past said comparing means, means under the control of said comparing means for causing upon disagreement of said index marks with said perforations said printing mechanism and record feeding means to remain inactive and to cause actuation of the address plate feeding means to feed the subsequent address plate to comparing position while upon agreement of said index marks with said perforations said comparing means cause actuation of the printing mechanism to print the address plate upon the corresponding perforated record and actuation of the record feeding means to feed the subsequent record to comparing position, and means for selectively changing the control of said comparing means upon the plate feeding means to render upon agreement of said index marks with said perforations the plate feeding means inactive or to cause actuation of the same to feed the subsequent address plate to comparing position.
19. In an automatic addressing machine being under the joint control of designation perforations spaced apart along a continuous record sheet and of index marks associated to address plates, a printing mechanism for printing the address plates upon the record sheet sections bearing the designation perforations, means for feeding said perforated record sheet sections one by one past said printing mechanism and means for feeding said address plates one by one past said printing mechanism, means for comparing the index marks associated to the address plate being in printing position with the designation perforations of the record sheet section being in printing position, and means under the control of said comparing means for causing upon disagreement of said index marks with said perforations said printing mechanism and record sheet feeding means to remain inactive and to cause actuation of the address plate feeding means to feed the subsequent address plate to printing position while upon agreement of said index marks with said designation perforations said comparing means cause actuation of the printing mechanism to print the address plate upon the corresponding perforated record sheet section and actuation of the record sheet feeding means to feed the subsequent record sheet section to printing position, and means for selectively changing the control of said comparing means upon the address plate feeding means to render upon agreement of said index marks with said designation perforation the address plate feeding means inactive or to cause actuation of the same to feed the subsequent address plate to printing position.
20. In an automatic addressing machine being under the joint control of designation perforations spaced apart along a continuous record sheet and of index marks associated to address plates, a printing mechanism for printing the address plates upon the record sheet sections bearing the designation perforations, means for feeding said perforated record sheet sections one by one past said printing mechanism, said feeding means being under the control of guide holes in the record sheet, one hole being coordinated to each designation perforation and means for feeding said address plates one by one past said printing mechanism, means for comparing the index marks associated to the address plate being in printing position with the designation perforation of the record sheet section being in printing position, said feeding means being stopped under the control of a guide hole in the record sheet and said comparing means becoming thereafter automatically active and means under the control of said comparing means for causing upon disagreement of said index marks with said perforations said printing mechanism and record feeding means to remain inactive and to cause actuation of the address plate feeding means to feed the subsequent address plate to printing position while upon agreement of said index marks with said designation perforations said comparing means cause actuation of the printing mechanism to print the address plate upon the corresponding perforated record sheet section and actuation of the record sheet feeding means to feed the subsequent record sheet section to printing position, and means for selectively changing the control of said comparing means upon the address plate feeding means to render upon agreement of said index marks with said designation perforation the address plate feeding means inactive or to cause actuation of the same to feed the subsequent address plate to printing position.
21. In an automatic addressing machine being under the joint control of designation perforations spaced apart along a continuous record sheet and of index marks associated to address plates, a printing mechanism for printing the

- address plates upon the record sheet sections bearing the designation perforations, means for comparing the index marks associated to the address plate being in comparing position with the 5 designation perforations of the record sheet section, the designation being in comparing position, means for feeding said perforated record sheet sections one by one past said comparing means and means for feeding said address plates one by one past said 10 comparing means, means under the control of said comparing means for causing upon disagreement of said index marks with said perforations said printing mechanism and record sheet feeding means to remain inactive and to cause actuation 15 of the address plate feeding means to feed the subsequent address plate to comparing position while upon agreement of said index marks with said designation perforations said comparing means cause actuation of the printing mechanism 20 to print the address plate upon the corresponding perforated record sheet section and actuation of the record sheet feeding means to feed the subsequent record sheet section to comparing position, and means for selectively changing the 25 control of said comparing means upon the address plate feeding means to render upon agreement the address plate feeding means inactive or to cause actuation of the same to feed the subsequent address plate to comparing position.
- 30 22. In an automatic addressing machine being under the joint control of designation perforations spaced apart along a continuous record sheet and of index marks associated to address plates, a printing mechanism for printing the address plates upon the record sheet sections bearing the designation perforations, means for comparing the index marks associated to the address plate being in comparing position with the designation perforation of the record sheet 35 section being in comparing position, means for feeding said perforated record sheet sections one by one past said comparing means, said feeding means being stopped under the control of guide holes in the record sheet, one hole being coordinated to each designation perforation, means for feeding said address plates one by one past said comparing means, said comparing means becoming automatically active upon stopping of said feeding means under the control of a guide hole, 40 means under the control of said comparing means for causing upon disagreement of said index marks with said perforations said printing mechanism and record sheet feeding means to remain inactive and to cause actuation of the address 45 plate feeding means to feed the subsequent address plate to comparing position while upon agreement of said index marks with said designation perforations said comparing means cause actuation of the printing mechanism to print the address plate upon the corresponding perforated record sheet section and actuation of the record sheet feeding means to feed the subsequent record sheet section to comparing position, and means for selectively changing the control of said 50 comparing means upon the address plate feeding means to render upon agreement the address plate feeding means inactive or to cause actuation of the same to feed the subsequent address plate to comparing position.
- 55 23. In an automatic printing machine being under the joint control of perforated records and of index marks associated to address plates, a printing mechanism for printing the address plates upon the records themselves bearing the 55 designation perforations, means for feeding said perforated record sheet sections one by one past said printing mechanism and means
- records and means for feeding said address plates through the machine, means for comparing the index marks associated to the address plates with the perforations on said records, and means under the control of said comparing means for causing said printing mechanism to print the address plate upon the corresponding perforated record itself upon agreement of said index marks with said perforations and for actuating the record feeding means and causing the address plate feeding means to remain inactive while upon disagreement the printing mechanism and record feeding means remain inactive whereas the address plate feeding means are actuated.
24. In an automatic addressing machine being under the joint control of perforated records and of index marks associated to address plates, a printing mechanism for printing the address plates upon the records themselves bearing the perforations, means for feeding said perforated records one by one past said printing mechanism and means for feeding said address plates one by one past said printing mechanism, means for comparing the index marks associated to the address plate being in printing position with the perforations on the record being in printing position, and means under the control of said comparing means for actuating upon agreement of said index marks with said perforations the printing mechanism to print the address plate 30 upon the corresponding perforated record and for actuating the record feeding means to feed the subsequent record to printing position and causing the address plate feeding means to remain inactive while upon disagreement of said index 35 marks with said perforations said comparing means cause said printing mechanism and record feeding means to remain inactive and cause only actuation of the address plate feeding means to feed the subsequent address plate to printing 40 position.
25. In an automatic addressing machine being under the joint control of perforated records and of index marks associated to address plates, a printing mechanism for printing the address plates upon the records themselves bearing the perforations, means for comparing said perforated records with the index marks associated to the address plates, means for feeding said records one by one past said comparing means and 45 means for feeding said address plates one by one past said comparing means, means under the control of said comparing means for causing upon agreement of said index marks with said perforations the printing mechanism to print the address plate upon the corresponding perforated record and for actuating the record feeding means to feed the subsequent record to said comparing means and cause the address plate feeding means to remain inactive while upon disagreement of said index marks with said perforations said comparing means cause said printing mechanism and record feeding means to remain inactive and cause only actuation of the address plate feeding means to feed the subsequent address plate to said comparing means.
26. In an automatic addressing machine being under the joint control of designation perforations spaced apart along a continuous record sheet and of index marks associated to address plates, a printing mechanism for printing the address plates upon the record sheet sections bearing the designation perforations, means for feeding said perforated record sheet sections one by one past said printing mechanism and means

- for feeding said address plates one by one past said printing mechanism, means for comparing the index marks associated to the address plate being in printing position with the designation perforations of the record sheet section being in printing position, and means under the control of said comparing means for actuating upon agreement of said index marks with said designation perforation the printing mechanism to print the address plate upon the corresponding perforated record sheet section and for actuating the record sheet feeding means to feed the subsequent record sheet section to printing position and causing the plate feeding means to remain inactive while upon disagreement of said index marks with said designation perforations said comparing means cause said printing mechanism and record sheet feeding means to remain inactive and cause only actuation of the address plate feeding means to feed the subsequent address plate to printing position.
27. In an automatic addressing machine being under the joint control of designation perforations spaced apart along a continuous record sheet and of index marks associated to address plates, a printing mechanism for printing the address plates upon the record sheet sections bearing the designation perforations, means for feeding said perforated record sheet sections one by one past said printing mechanism, said feeding means being under the control of guide holes in the record sheet one hole being coordinated to each designation perforation, and means for printing said address plates one by one past said printing mechanism, means for comparing the index marks associated to the address plate being in printing position with the designation perforations of the record sheet being in printing position, said feeding means being stopped under the control of a guide hole in the record sheet and said comparing means becoming thereafter automatically active and means under the control of said comparing means for actuating upon agreement of said index marks with said perforations the printing mechanism to print the address plate upon the corresponding perforated record sheet section and for actuating thereafter the record sheet feeding means to feed the subsequent record sheet section to printing position and causing the plate feeding means to remain inactive while upon disagreement of said index marks with said designation perforation said comparing means cause said printing mechanism and record sheet feeding means to remain inactive and cause only actuation of the address plate feeding means to feed the subsequent address plate to printing position.
28. In an automatic addressing machine being under the joint control of designation perforations spaced apart along a continuous record sheet and of index marks associated to address plates, a printing mechanism for printing the ad-
- dress plates upon the record sheet sections bearing the designation perforations, means for comparing the index marks associated to the address plate being in comparing position with the designation perforations of the record sheet section being in comparing position, means for feeding said perforated record sheet sections one by one past said comparing means and means for feeding said address plates one by one past said comparing means, means under the control of said comparing means for actuating upon agreement of said index marks with said designation perforation the printing mechanism to print the address plate upon the corresponding perforated record sheet section and for actuating the record sheet feeding means to feed the subsequent record sheet section to said comparing means and cause the plate feeding means to remain inactive while upon disagreement of said index marks with said designation perforations said comparing means cause said printing mechanism and record sheet feeding means to remain inactive and cause only actuation of the address plate feeding means to feed the subsequent address plate to comparing position.

MICHAEL MAUL.
